TIERED PLANTER

Rean Otis Titus, 4436 Mt. Elliott Ave., Detroit, Mich.

Filed Jan. 4, 1965, Ser. No. 83,263

Term of patent 14 years

(Cl. D35—3)

FIG.1

FIG. 2

FIG. 3

FIG. 4

FIG. 5

FIGURE 1 is a perspective view looking down on the top and two sides of a tiered planter, embodying my new design.

The sides of the tiered planter design not shown in the figures are substantially the same as the sides shown.

I claim:

The ornamental design for a tiered planter, substantially as shown and described.
